(57) **CLAIM**

The ornamental design for a tire, as shown and described.

DESCRIPTION

FIG. 1 is a perspective view of a tire showing our new design;

FIG. 2 is a front view thereof, the rear, top and bottom view being identical thereto;

FIG. 3 is a right side view thereof, the left side view being identical thereto;

FIG. 4 is an enlarged view of the indicated portion of FIG. 1; and,

FIG. 5 is an enlarged view of the indicated portion of FIG. 2.

The dashed broken lines illustrate portions of the tire and form no part of the claimed design. The dot-dashed broken lines define the bounds of the claimed design and form no part thereof. The tire pattern is understood to repeat uniformly throughout the circumference of the tire, as shown schematically in solid lines.
